ALARM CLOCK

Elof L. Carlson, Bristol, Conn., assignor to The E. Ingraham Company, Bristol, Conn., a corporation

Application May 24, 1933, Serial No. 672,542

15 Claims. (Cl. 58—38)

This invention relates to alarm clocks, and more particularly to the striker-actuating mechanism of alarm clocks.

In order to awaken persons known as heavy sleepers, it has been necessary heretofore to provide alarm clocks with alarm-sounding means which produce sound of considerable violence. Such violent sound, however, especially shocks or startles persons known as light sleepers, and alarm clocks have therefore sometimes been provided with a double alarm, the first of which produces a soft or gentle alarm which is sufficient to arouse light sleepers, who thereupon shut off the alarm. But if a sleeper does not awaken as a result of the gentle alarm, after a certain period of time the loud or violent alarm sounds.

A considerable objection to the combined soft and loud alarms, as heretofore made, is that they require much additional mechanism with consequent increased cost.

I have devised an alarm, however, of great simplicity and low cost which can be made to accomplish substantially all that is accomplished by the previously described combined soft and loud alarms, and which in addition can be made to operate to give a comparatively low intensity of sound, thus awakening sleepers without shocking or startling them and with minimum disturbance to other persons.

30 A characteristic of my invention resides in providing an alarm in which the striker is actuated at varied or irregular intervals, or varied or irregular intensities or combined varied or irregular intervals and intensities. Thus, even though the sound be of low intensity, the lack of uniformity in the intervals and/or intensities between successive beats during an alarm-sounding period, disturbs and awakens the sleeper.

40 An object of this invention, therefore, is to provide improved alarm-sounding mechanism of great simplicity and low cost, which shall be adequate to arouse both heavy and light sleepers without shock, and with a minimum of disturbance to other persons.

The above and other objects and advantages will appear from the following description, appended claims and accompanying drawings forming a part of this specification.

50 In the accompanying drawings, in which certain ways of carrying out the invention are shown for illustrative purposes:

Fig. 1 is a front elevation, with part of the front movement-plate broken away, of an alarm-clock movement embodying this invention;

Fig. 2 is a perspective view of the striker or hammer-arm;

Fig. 3 is a face elevation of the hammer-actuating wheel assembled with the center arbor;

Fig. 4 is a left-end elevation of Fig. 1;

Fig. 5 is a perspective view of the shut-off lever;

Fig. 6 is a view similar to Fig. 3 of a modified form of hammer-actuating wheel; and

Fig. 7 is a view similar to Fig. 3 of another modified form of hammer-actuating wheel.

Referring to the drawings, 10 and 11 are the front and rear movement-plates, held together by the pillars 12 and carrying the parts of the movement of an alarm clock.

The particular movement illustrated has an 15 electric motor 13, preferably synchronous, which is geared down within the casing 14 to provide an arbor 15 in line with the center or seconds arbor 16 and in driving engagement with the latter by means of a spur-gear clutch-member 20 20 17 engaging in an internal-gear clutch-member 18. Arbors 15 and 16 rotate clockwise at the rate of one revolution per minute.

The clutch-member 18 has a reduced portion 19 which extends through the hammer-actuating wheel 20 and is riveted or otherwise attached thereto, and the clutch-member 18 also has a central opening in which the center or seconds arbor 16 is secured by means of a drive fit or otherwise.

The spur-gear clutch-member 17 is in driving engagement with the time-train, generally indicated by the numeral 21, and by means of which the minute-sleeve 22 and hour-sleeve 23 are driven.

35 The bell or alarm-sounding member 24 is supported by the bracket 25 which is bolted to the rear movement-plate 11. A hammer-arm 26 is secured on an arbor 27 pivoted in the movement-plates 10 and 11, and carries a hammer-actuating finger 28 adapted to engage with cam- or actuating-elements 29 formed on the periphery of the hammer-actuating wheel 20. The extension 30 of the hammer-arm is engaged by a spring 31 anchored in the hole 32 in the front movement-plate 10, which spring tends to pull the extension 30 upwardly about the pivot of the arbor 27 to thrust the hammer 33 downwardly into striking engagement with the bell 24.

The rear upward extension 34 of the hammer-arm 26 forms a hammer-tail adapted to strike against the upper left pillar 12 (Fig. 1) to resiliently limit the downward swinging movement of the hammer 33. Due to the slenderness and resilience of the hammer-tail and the hammer-

arm, and due to the weight of the hammer 33, when one of the projections or cams 29 lifts and releases the hammer-actuating finger 28, the spring 30 causes the hammer 33 to be swung 5 downwardly toward the bell 24 from its dotted position shown in Fig. 1, until the hammer-tail 34 strikes the upper left pillar 12 (Fig. 1) and tends to stop the hammer in the position in which it is shown in full lines in Fig. 1, but due to the 10 inertia of the hammer 33 and the resilience or spring of the hammer-tail and hammer-arm, the hammer 33 moves downwardly until it strikes the bell 24, whereupon it springs back to its normal position slightly above the bell, as shown in full 15 lines in Fig. 1.

35 is the usual hand-set arbor or staff. The alarm-set arbor or staff 36, through the usual suitable gearing, actuates the arbor 37 which has secured thereto the alarm-cam finger 38. The 20 alarm-wheel 39 is fixed to the alarm-cam sleeve 40 which is rotatable and slidably on the arbor 37 and normally pushed toward the front movement-plate 10 by means of the alarm-control spring 41 which is secured to the front movement-plate at 42, and extends past the arbor 37 and is 25 provided with an alarm-control finger 43 having a cam-surface 44.

By means of the alarm-set arbor or staff 36, the alarm-cam finger 38 is rotated to bring it into any desired alarm-time position, in accordance 30 with an alarm-dial (not shown) in the usual and well-known way.

The alarm-wheel 39 is in driven engagement with the time-train which drives the minute- and 35 hour-sleeves 22 and 23. When the alarm-wheel 39 has rotated to the position where the alarm is to sound, the notch 45 in the cam-sleeve comes opposite the cam-finger 28, thereby permitting the alarm-control spring 41 to push the alarm-wheel 39 and cam-sleeve 40 axially along the staff 37 and thereby permit the cam-surface 44 to swing laterally out of the path which it normally occupies in resting against the upwardly-extending portion 46 of the hammer-arm 26, 40 thereby permitting the hammer 33 to move downwardly from the dotted position shown in Fig. 1 to its full-line position, thereby bringing the hammer-actuating finger 28 into position to be lifted by the cam-elements 29 formed on the periphery of the hammer-actuating wheel 20, which at all times rotates at one R. P. M. in the type of clock illustrated in the drawings.

Each time one of the cam-elements 29 raises 45 and releases the hammer-actuating finger 28, the hammer 33 is caused to strike a blow against the bell 24. This alarm-sounding action continues until the hammer 33 is lifted and held in its raised dotted-line position (Fig. 1). The hammer is raised and held in this position by means 50 of the cam-surface 44 on the alarm-control finger 43, which is gradually forced into engagement with the upwardly-extending portion 46 of the hammer-arm 26 as the cam-sleeve 40 is rotated by the time-train to cause the cam-surface 47 of the alarm-cam sleeve 40 to wipe against the alarm-cam finger 38 and shift the alarm-cam sleeve 40 longitudinally of the arbor 37 to 55 push the alarm-control spring 41, with its integral alarm-control finger 43, to move the cam-surface 44 into forcible engagement with the portion 46 of the hammer-arm 26 to raise and hold the hammer 33 in the dotted-line position (Fig. 1).

A shut-off lever 48 is pivoted at 49 and is normally thrust upward against the limit-finger 50

5 by means of the spring 51 and has a lateral extension 52 provided with a bifurcated end 53 adapted to be engaged and pushed downwardly and pulled upwardly by any suitable means, such as an alarm-shut-off plunger (not shown). The 10 shut-off lever 48 is provided with a latching-end 54 which, when forced downwardly, rides along the cam-surface 55 of the hammer-tail 34, so as to swing the hammer-arm upwardly to bring the hammer 33 in the inactive dotted position shown 15 in Fig. 1, whereupon the latching-end 54 snaps beneath the keeper 56 to hold the hammer in its 20 inoperative position.

When it is desired to release the hammer in order that it may be actuated in time to give an 15 alarm, the alarm-shut-off plunger (not shown), which engages the bifurcated end 53, is pulled upwardly, which causes the latch-end 54 to snap upwardly past the keeper 56 so as to release the hammer-arm 26, which is then swung down- 20 wardly to operative position by means of the spring 31.

Inasmuch as the hammer-actuating wheel 20 rotates at uniform speed, the times at which the hammer 33 strikes the bell 24 will be determined 25 by the relative spacing between the cam-elements 29 around the wheel 20, in the form of hammer-actuating wheel shown in Figs. 1 and 3. The cam-elements 29 are arranged in successive 30 groups of one, two and three cam-elements, so that if the hammer-actuating finger 28 happens to descend at a location between the one-and-three group of cam-elements, the hammer will be caused to strike one, one-two, one-two-three (as the hammer-actuating wheel 20 rotates clockwise) and then repeat this cycle over indefinitely.

If the hammer-actuating finger 28 happens to descend at some other location, the first contact of the hammer with the bell may be to give two blows or three blows, depending on whether it 40 descends just ahead of a two group or a three group of cam-elements, but in any case, regardless of where the hammer-actuating finger 28 happens to start, the alarm will be produced as a succession of varied or irregular beats which 45 have a powerful awakening quality, even though the intensity of the blow on the bell be very mild.

In Fig. 6 is shown a modified form of actuating-wheel 57 in which a greater range of variation 50 is produced in the beats or blows struck upon the bell 24 by means of a greater range of variation in the grouping of the cam-elements 29.

In Fig. 7 is shown another modified form of actuating-wheel 58 in which certain of the cam-elements are of differing height to vary the intensity of the beats or blows struck upon the bell 24. The cam-elements 29 are of the same height, while the cam-elements 59 are somewhat higher than the cam-elements 29 and cam-elements 60 are somewhat higher than cam-elements 59. It will be observed that this form of construction is adapted to actuate the striker at combined varied intervals and intensities. It will be obvious that this construction could be further 65 varied in other ways, including having the top points of all the cam-elements at equal distances from each other to produce beats or blows of varied intensities but at uniform intervals.

The invention may be carried out in other specific ways than those herein set forth without departing from the spirit and essential characteristics of the invention, and the present embodiments are therefore to be considered in all respects as illustrative and not restrictive, and all 70 75

changes coming within the meaning and equivalency range of the appended claims are intended to be embraced therein.

I claim:

5. 1. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having elements adapted to actuate said striker at varied intervals during an alarm-sounding period.
10. 2. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having varied-spaced elements adapted to actuate said striker at varied intervals during an alarm-sounding period.
15. 3. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having elements adapted to actuate said striker at varied intervals during an alarm-sounding period.
20. 4. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having varied-spaced elements adapted to actuate said striker at varied intervals during an alarm-sounding period.
25. 5. An alarm clock comprising: time mechanism and operating mechanism therefor, an alarm-sounding member, a striker for striking said alarm-sounding member, and striker-actuating mechanism adapted to actuate said striker at varied intervals and intensities during an alarm-sounding period.
30. 6. An alarm clock comprising: time mechanism and operating mechanism therefor, an alarm-sounding member, a striker for striking said alarm-sounding member, and striker-actuating mechanism adapted to actuate said striker at varied intensities in repeated cycles during an alarm-sounding period.
35. 7. An alarm clock comprising: time mechanism and operating mechanism therefor, an alarm-sounding member, a striker for striking said alarm-sounding member, and striker-actuating mechanism adapted to actuate said striker at varied intervals and intensities in repeated cycles during an alarm-sounding period.
40. 8. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having elements adapted to actuate

said striker at varied intensities during an alarm-sounding period.

9. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having elements adapted to actuate said striker at varied intervals and intensities 10 during an alarm-sounding period.

10. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having elements adapted to actuate said striker at varied intensities in repeated cycles 15 during an alarm-sounding period.

11. An alarm clock comprising: time mechanism including a center arbor, operating mechanism for said time mechanism, an alarm-sounding member, a striker for striking said alarm-sounding member, and striker-actuating mechanism including a wheel mounted on said center arbor and having elements adapted to actuate said striker at varied intervals and intensities 20 in repeated cycles during an alarm-sounding period.

12. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having elements adapted to actuate said striker at varied 25 intensities during an alarm-sounding period.

13. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having elements adapted to actuate said striker at varied 30 intensities during an alarm-sounding period.

14. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having elements adapted to actuate said striker at varied 35 intensities during an alarm-sounding period.

15. An electric alarm clock comprising: time mechanism including a seconds arbor, an electric motor actuated mechanism for rotating said seconds arbor, an alarm-sounding member, a striker for striking said alarm-sounding member, and striker-actuating mechanism including a wheel mounted on said seconds arbor and having elements adapted to actuate said striker at varied 40 intensities in repeated cycles during an alarm-sounding period.
